UNITED STATES PATENT OFFICE.

FRANK A. BORZYCH, OF MINATARE, NEBRASKA.

SPIRAL PLATE CONDENSER.

Application filed February 15, 1926. Serial No. 88,391.

My invention relates to improvements in spiral plate condensers, and it consists in the combinations, constructions, and arrangements herein described and claimed.

5 In the standard condenser, one-half the circumference of the dial is divided into either one hundred equal parts or one hundred and eighty equal parts. This of course means that all of the stations are crowded into one-half a revolution of the dial. Certain condensers are provided with verniers for permitting very fine adjustment. But even these attachments do not overcome the trouble of tuning in the desired 10 station, because it will still be noted that all of the stations are still crowded into one-half a revolution of the condenser.

An object of my invention is to provide a spiral plate condenser which permits the dial 20 to be rotated through a number of revolutions between the points of minimum capacity of the condenser and maximum capacity, the dial being graduated throughout its entire circumference for this purpose, whereby 25 a very fine adjustment may be effected throughout the entire range of the condenser.

A further object of my invention is to provide a device of the type described which has means associated with the dial for showing the number of turns of the dial.

A further object of my invention is to provide a device of the type described which is relatively simple in construction, durable and efficient for the purpose intended.

35 Other objects and advantages will appear in the following specification, and the novel features of the invention will be particularly pointed out in the appended claims.

My invention is illustrated in the accompanying drawings, forming part of this application, in which

Figure 1 is a top plan view of the device,

Figure 2 is a front elevation of a portion of the device,

45 Figure 3 is a section along the line 3—3 of Figure 2,

Figure 4 is a section along the line 4—4 of Figure 1, and

50 Figure 5 is a section along the line 5—5 of Figure 1.

In carrying out my invention, I provide supporting members 1 and 2, these members being preferably made of insulating material. It should be noted at this point that 55 the drawings show a condenser of rather large proportions, this showing being made

for the purpose of clarity. It is obvious that the condenser may be made of any size desired, the size being controlled by the capacity desired.

60

The members 1 and 2 are connected together by posts 3, these posts having reduced threaded portions 4, see Figure 1, for passing through openings in the members 1 and 2. The threaded portions project through 65 the members and receive nuts 5. In the drawings, I have shown three of these posts. In case a large condenser is to be made, six or more posts may be provided.

One of the posts, see Figure 1, carries a 70 lock nut 6 which is adapted to clamp a wire 7 between it and the nut 5. This arrangement forms the stator plate terminal connection for the condenser.

To the posts 3, I secure a spiral stator 75 plate 8. This plate is made of conducting material and may be composed of a plurality of plates connected together for forming a good electrical connection between the plates. In Figure 5, I show how the posts 80 are provided with recesses 9 for receiving the spiral stator plate 8.

I will now describe the means for moving a spiral rotor plate 10 between the different turns of the spiral stator plate, whereby the 85 capacity of the condenser may be changed at will. A screw 11 has a reduced threaded portion 12 which passes through an opening 13 in the supporting member 1. Upon the reduced threaded portion 12, I mount 90 adjusting nuts 14 and 15. These nuts clamp to the supporting member 1 and may be adjusted upon the portion 12 for moving the screw 11 longitudinally when adjusting the spiral rotor 10 with respect to the spiral stator. The nuts 14 and 15 also prevent rotation of the screw 11 with respect to the supporting members 1 and 2.

A threaded terminal 16 projects from the portion 12 and is adapted to receive a lock 100 nut 17, see Figure 1. The lock nut 17 clamps a wire 18 to the screw 11, thus forming a terminal for the rotating element 10. The wires 7 and 18 may be connected to any circuit using a condenser, such as a radio circuit.

Upon the screw 11, I mount a rotor carrying nut 19. This nut has a spiral groove 21 therein for receiving the spiral rotor plate 10. The plate is rigidly secured to the nut 110 and is adapted to be rotated when the nut is rotated.

The means for rotating the nut upon the screw 11 consists in the present instance of a pair of rotor driving pins 22. These pins are slidably received in bores 23 in the nut 19, and have their ends secured in a flange 24 of a driving sleeve 25. The driving sleeve in turn has a recess 26 for receiving a reduced end 27 of the screw 11. It will be seen from this construction that a rotation of the driving sleeve 25 will rotate the nut 19 upon the screw 11. The driving sleeve is mounted in a bushing 28, the bushing being disposed in an opening in the supporting member 2 and being secured thereto by a nut 29.

The screw 11 preferably has a compound thread thereon, the pitch of the thread being the same as the pitch of the spiral plates 8 and 10. In this way, a rotation of the nut 19 will cause the spiral rotor to weave inside the spiral stator, the turns of the rotor being spaced midway between the turns of the stator. As heretofore stated, adjustment of the nuts 14 and 15 will move the screw 11 for permitting the longitudinal movement of the rotor with respect to the stator.

The members 1 and 2, together with the parts that they support, may be secured to a panel board 30, if desired. I provide stub posts 31 for securing the member 2 to the panel board 30. In the present drawing, I have shown three of these posts, and have shown the posts 31 as being spaced between the posts 3. The posts 31 are disposed adjacent to the driving sleeve 25, and a dial 32 is provided for covering the nuts 33 of the posts 31. The driving sleeve 25 projects through an opening 34 in the panel board 30, and has its reduced end 35 provided with a cap 36. The cap in turn has a projection 37 receivable in a recess in the dial 32. A set screw 38 locks the cap 36 to the driving sleeve 25. It is obvious that this specific construction may be changed without departing from the spirit and scope of my invention.

In Figure 2, I show the front face of the dial 32 as being graduated into one hundred equal parts at 39. The screw 11 is long enough to permit the dial 32 to be rotated through a number of revolutions. Some designating means is necessary for indicating the number of revolutions made by the dial 32. This means may be a dial having numbers thereon, these numbers advancing one digit for each revolution of the dial, or the numbers may refer to various wave lengths, such as the number 100 appearing when the dial has made one complete revolution, and the number 150 appearing when the dial has made an additional half revolution, etc.

In Figures 1 and 4, I show a specific mechanism for indicating the number of revolutions of the dial, this mechanism comprising

a dial actuated by a cord connection between the dial and the driving sleeve 25. It is obvious that a gear connection between these two elements may be made without departing from the spirit and scope of my invention.

I mount a casing 40 upon a projection 41 carried by one of the posts 3. A collar 42 bears against the casing and keeps the casing in abutting relation with the inner surface of the panel board 30. The casing is provided with a groove 43 therein, this groove receiving a cable 44. The cable has an end secured to the casing 40, and has its other end secured to the driving sleeve 25. It will further be noted from Figure 4 that the cable is passed over an idler pulley 45. A dial 46 is secured to the casing 40 and has numbers 47 thereon which are adapted to be brought into registration with an opening 48 in the panel board 30. A coil spring 49 is connected to the member 41 and to the casing 40 in a manner to cause the casing to wind up the cable 44 thereon as fast as the cable is unwound from the driving sleeve 25.

From the foregoing description of the various parts of the device, the operation thereof may be readily understood. Let us assume that the condenser has ten complete revolutions of the spiral stator and spiral rotor and compare this with a standard condenser which can only be swung through one-half of a revolution. Assume that the dial of the standard condenser has one-half of its circumference graduated into one hundred equal parts. The dial 32 is also graduated into one hundred equal parts, but these one hundred parts are spread over the entire circumference, and it will therefore appear that the graduations on the dial 32 are twice as large as those on the dial of the standard condenser. In addition to this, if ten complete revolutions are provided in the spiral stator and spiral rotor, the dial 32 may therefore be rotated through ten complete revolutions. Let us further assume that the capacity of the two condensers is the same. It will therefore be seen that the dial 32 may be swung into one thousand different positions; whereas the dial of the standard condenser may be swung into only one hundred different positions, these positions being one-half the size of the graduations on the standard dial.

It will further be apparent that a movement of the dial 32 through ten graduations is equal to a movement of one graduation in the standard dial. It is therefore obvious that this condenser can accurately tune in stations if the condenser is employed in a radio receiving set, which are almost impossible to tune in with the standard condenser, due to the fact that the stations are so close together on the dial.

The dial 46 working in combination with the dial 32 provides a simple mechanism

for indicating the exact position the spiral rotor 10 is disposed in with respect to the spiral stator 8. It will be noted from Figure 3 that a rotation of the dial 32 will cause the pins 22 to rotate the nut 19 upon the screw 11 and move the spiral rotor into mesh with or out of mesh from said spiral stator. This movement of course changes the capacity of the condenser. The device 10 is compact in construction and operates efficiently for the purpose intended.

I claim:

1. A spiral condenser, comprising a pair of spaced-apart supporting members, a 15 sleeve rotatably carried by one of said supporting members and having a central bore at one end, a dial secured to the other end, a threaded shaft having a cylindrical extension arranged to enter in and be supported by the sleeve, said shaft having a reduced threaded portion arranged to pass through the other of said supporting members, adjusting nuts carried by the reduced threaded portion of the shaft for adjusting 25 the position of the shaft with respect to the supports, a spiral stator, a traveling nut carried by said threaded shaft and having longitudinal bores, drive pins extending through said bores and having their ends 30 secured to said sleeve, a spiral rotor carried by the nut and adapted to enter between the convolutions of the spiral stator when the nut is rotated, and means for indicating the relative positions of the rotor and stator.
- 35 2. A spiral condenser, comprising a pair of spaced-apart supporting members, a sleeve rotatably carried by one of said sup-

porting members and having a central bore at one end, a dial secured to the other end, a threaded shaft having an extension arranged to enter in and be supported by the sleeve, means for adjustably securing the opposite end of the shaft to the other of said supporting members, a spiral stator, a traveling nut carried by said threaded shaft and having longitudinal bores, drive pins extending through said portion and having their ends secured to said sleeve, a spiral rotor carried by the nut and adapted to enter between the convolutions of the spiral stator when the nut is rotated, and means for indicating the relative positions of the rotor and stator.

3. A spiral condenser, comprising a pair of spaced-apart supporting members, a 55 sleeve rotatably carried by one of said supporting members, a dial secured to the sleeve at one end, a threaded shaft supported by the sleeve at one end, means for supporting said shaft at the other end on the other of said supporting members, said means permitting the longitudinal adjustment of the shaft with respect to the supporting member and the sleeve, a spiral stator, a traveling nut carried by said 60 threaded shaft, means carried by the sleeve for rotating the nut, a spiral rotor carried by the nut and adapted to enter between the convolutions of the spiral stator when the nut is rotated, and means for indicating the relative positions of the rotor and stator.
